UNITED STATES PATENT OFFICE

JOHN ARTIM, OF GARFIELD, NEW JERSEY, ASSIGNOR TO H. B. WIGGIN'S SONS COMPANY,
OF BLOOMFIELD, NEW JERSEY, A CORPORATION OF NEW JERSEY

DESIGN FOR A WALL PAPER OR SIMILAR ARTICLE

Application filed October 11, 1930. Serial No. 37,238. Term of patent 3½ years.

To all whom it may concern:

Be it known that I, JOHN ARTIM, a citizen of the United States, residing at Garfield, in the county of Bergen and State of New Jersey, have invented a new, original, and ornamental Design for Wall Paper or Similar Article, of which the following is a specification, reference being had to the accompanying drawing, forming a part thereof.

The figure is a front face view of the wall paper or similar article of my new design with one unit of the recurring design indicated by enclosing lines.

I claim:

The ornamental design for a wall paper or similar article, as shown and described.

JOHN ARTIM.
